CLAIM

We claim the ornamental design for a lock, as shown and described.

DESCRIPTION

FIG. 1 is a perspective view of the claimed design in a first environment;

FIG. 2 is a front view of the claimed design of FIG. 1;

FIG. 3 is a rear view of the claimed design of FIG. 1;

FIG. 4 is a right side view of the claimed design of FIG. 1;

FIG. 5 is a left side view of the claimed design of FIG. 1;

FIG. 6 is a top view of the claimed design of FIG. 1;

FIG. 7 is a bottom view of the claimed design of FIG. 1;

FIG. 8 is a perspective view of the claimed design in a second environment;

FIG. 9 is a front view of the claimed design of FIG. 8;

FIG. 10 is a rear view of the claimed design of FIG. 8;

FIG. 11 is a right side view of the claimed design of FIG. 8;

FIG. 12 is a left side view of the claimed design of FIG. 8;

FIG. 13 is a top view of the claimed design of FIG. 8; and,

FIG. 14 is a bottom view of the claimed design of FIG. 8.

The ornamental design that is claimed is shown in solid lines in the figures. Broken lines of equal or substantially equal length dashes in the drawings are for illustrative purposes only and form no part of the claimed design. Broken lines formed of unequal length dashes (i.e., dash-dot) represent the boundaries of the claimed design.
